UNITED STATES PATENT OFFICE.

WALTER R. KAHNS, OF CHICAGO, ILLINOIS, ASSIGNOR TO J. H. WHITE MANUFACTURING COMPANY, OF BROOKLYN, NEW YORK, A CORPORATION OF NEW YORK.

LIGHTING-FIXTURE.

1,159,042.

Specification of Letters Patent.

Patented Nov. 2, 1915.

Application filed January 15, 1915. Serial No. 2,299.

To all whom it may concern:

Be it known that I, WALTER R. KAHNS, a citizen of the United States, residing at Chicago, in the county of Cook and State 5 of Illinois, have invented an improvement in Lighting-Fixtures, of which the following is a specification.

My present invention relates to that class of electric lighting fixtures giving a candle 10 effect, in which a porcelain or glass tube or metal cylinder is employed to represent the candle, and a metallic cup is attached to a supporting arm or bracket, into which cup the lower end of the candle is inserted, such 15 candle-surrounding the lamp socket and its support carrying the conductor wires. Such cups interfere with the work of wiring, unless first removed from the bracket or support, and the candle is liable to be accidentally displaced, and where of glass or 20 porcelain, is very easily broken.

The object of my invention is to dispense entirely with the cups, to provide an unbreakable candle, securely held in position, 25 and at the same time give the same appearance and effect as when the usual glass or porcelain candles and separate metallic cups are employed.

The details of the invention are herein- 30 after particularly described.

In the accompanying drawing,—Figure 1 is an elevation showing my invention attached to a fixture. Fig. 2 is a vertical section.

Similar reference characters indicate like 35 parts in both figures.

10 designates a hollow metallic cylinder formed with a transverse annular rib 11. The surface of this cylinder above the rib 40 11 is coated with a substance to give it a contrasting appearance to the rib and that part of the cylinder below the same. The material employed for coating the upper surface of the cylinder may be of any desired character or color, but I prefer to use white enamel.

12, Fig. 1, indicates the coated or enamelled surface of the cylinder.

While my invention is applicable to chandeliers or other lighting fixtures in which a number of candles are employed, I have shown it in Fig. 1 as attached to a bracket 13 supported in the ordinary manner against a side wall 14. The free end of this bracket 55 is provided with a screw threaded stud 15;

where the invention is applied to a chandelier or other fixture requiring a number of candles, arms carrying similar studs are provided on the fixtures.

16 indicates a shallow shell having an annular concave rim 17. The bottom of this shell 16 has an opening to permit the shell to be placed over the screw-threaded stud 15 on the end of the bracket.

18 designates a support for a lamp socket, 65 and is preferably tubular to receive the conductor wires, although it may be of any suitable character adapted to be screwed upon the screw-threaded stud 15. In the form shown, the lower end of the tube is 70 interiorly screw-threaded for such purpose. It will be readily seen that when this tube is screwed down upon the interior bottom surface of the shell 16, such shell is firmly held in position. The edge of the rim 17 of 75 this shell is provided on opposite sides with slots 19.

20 indicates small teats or projections on opposite sides of the cylinder 10 adjacent to its lower end. This lower end of the cylinder 80 is received within the annular rim 17 of the shell 16, its bottom edge resting upon the annular shoulder formed therein. In placing the end of the cylinder within the shell 16, the projections 20 are brought to 85 register with the slots 19 in the rim 17 and are then inserted therein and the cylinder given a slight turn, carrying the teats 20 under the edge of the rim 17, thus securing the cylinder against vertical movement or 90 accidental displacement.

By reference to Fig. 1 of the drawing, it will be seen that the lower part of the cylinder 10 with its rib 11, has the same outward and ornamental appearance as the metal 95 cup heretofore employed in fixtures of this character, while the upper part of the cylinder with its coating 12, gives the same candle effect as has heretofore been produced by the separate candles and cups heretofore 100 employed. It will be obvious that the lower portion of the cylinder, or that part representing the cup heretofore employed, may be of any desired shape or configuration, so long as its lower edge is adapted to fit into 105 the rim 17 of the shell 16.

By the employment of my invention, the use of glass or porcelain candles is rendered unnecessary; the cups heretofore required are entirely dispensed with, while the same 110

ornamental and candle effect is obtained. There is no danger of the candles in my device being accidentally displaced, and the same are readily put in position on the fixture, or removed therefrom, while the work of wiring and attachment of the lamp supports is greatly facilitated.

I claim as my invention:

1. In a lighting fixture, the combination 10 of a supporting arm provided on its free end with a screw-threaded stud, a shallow shell having an angular concave rim and interior annular shoulder fitted over said stud, a lamp socket support screwed upon said stud and clamping said shell in position, and a hollow metallic cylinder having a transverse annular rib formed thereon at a predetermined distance from its lower end, which end is fitted into the rim of said shell 20 and rests upon said shoulder.
2. In a lighting fixture, the combination 25 of a supporting arm provided on its free end with a screw-threaded stud, a shallow shell having an angular concave rim and interior annular shoulder fitted over said stud, a lamp socket support screwed upon said stud and clamping said shell in position, a hollow metallic cylinder having a transverse

annular rib formed thereon at a predetermined distance from its lower end, which 30 end is fitted into the rim of said shell and rests upon said shoulder, and coacting means upon the lower end of the cylinder and upon the rim of the shell for securing the cylinder against vertical movement or accidental displacement. 35

3. In a lighting fixture, the combination of a supporting arm provided on its free end with a screw-threaded stud, a shell having an annular concave rim provided with a 40 slot on two opposite sides, said shell having an opening in its bottom through which said stud is passed, a lamp socket support screwed upon said stud and clamping said shell in position, a hollow metallic cylinder 45 having a transverse annular rib, teats on opposite sides of said cylinder adjacent its lower end and adapted to enter the slots in the rim of said shell, whereby the said cylinder is held in position. 50

Signed by me this 8th day of January, 1915.

WALTER R. KAHNS.
